UNITED STATES PATENT OFFICE.

LEWIS LINCOLN LASKA, OF CORDOVA, TERRITORY OF ALASKA.

BATTERY-TESTER.

1,388,727.

Specification of Letters Patent. Patented Aug. 23, 1921.

Application filed August 9, 1919. Serial No. 316,411.

To all whom it may concern:

Be it known that I, LEWIS L. LASKA, a citizen of the United States, residing at Cordova, Territory of Alaska, have invented 5 certain new and useful Improvements in a Battery-Tester, of which the following is a specification.

This invention has for its object to provide a convenient and compact device for 10 testing the strength of dry batteries of the type used in flashlights.

Another object is the provision of a device of this character in which a series of incandescent lamps of varying voltages is 15 utilized for indicating the strength of the battery, the poles of the latter being engageable with conveniently accessible contact elements for completing the circuit from the battery to the respective lamps.

20 With these and other objects in view as will appear as the description proceeds the invention comprises the novel features of construction combination of elements and arrangement of parts which will be more 25 fully described in the following specification and set forth with particularity in the claims appended hereto.

Figure 1 represents a front elevation of the improved battery tester,

30 Fig. 2 represents a front elevation thereof, the cover plate being removed,

Fig. 3 represents a transverse sectional view through the tester,

Fig. 4 represents a perspective view of 35 the socket member for the detachable flexible conductor removed from the tester, and,

Fig. 5 represents a perspective view of the 40 expandable lamp socket removed from the body plate.

45 Referring to the drawing, wherein similar reference numerals designate corresponding parts throughout the several views, the numeral 5 indicates a body plate constructed of wood or other insulating material having a coat of shellac or other liquid coating composition applied thereto capable of rendering the material of the body plate water-proof.

50 A series of lamp sockets 6 and 14 is arranged adjacent one edge of the body plate 5 in a row extending longitudinally thereof and the sockets project through a row of apertures formed in a removable cover plate 7 which is secured in position upon a marginal flange 8 provided upon the body plate

5 by screws or equivalent fastening devices 9.

Each of the several lamp sockets 6 is formed with the usual internal screw threads to fit the externally screw threaded base 60 portion of an incandescent lamp 10 and the inner closed terminal thereof is provided in the side or threaded portion with an aperture receiving a contact strip 12 secured in position upon the body plate 5 by a screw 65 or equivalent fastening element 13. The lamp socket 14 at the end of the series 6 is formed with diametrically opposed slits 15 and, owing to the inherent resiliency of the material from which the lamp socket is constructed, the latter may be slightly expanded to accommodate lamps of varying sizes. The expandable lamp socket 14 is electrically connected with a contact strip 12 and the several strips are electrically connected by a conductor 16 extending along the front face of the body member 5 in spaced relation to one of the side flanges 70 thereof.

The contact strips 12 are secured in position by screws 17 having headed front terminals which overlie the contact strips 12 securely clamping the latter in engagement with the inner terminals of the sockets 6 and 14. Suitable insulators are interposed 85 between the screws 17 and the lamp sockets 6 and 14 and nuts 19 are fitted upon the rear screw threaded terminals of the screws which project through apertures formed in the body plate 5. The nuts 19 are preferably countersunk in the body plate and suitable insulation covers the nuts and screw terminals.

Medially off-set contact strips 18 are secured between the body plate and the nuts 95 19 whereby the screws 17 are electrically connected therewith and the opposite terminals of the off-set contact strips lie in facial abutment with the front of the body plate 5.

Screws 20 are fitted in the exposed terminals of the off-set contact strips 18 and secure the adjacent terminals of the several conductors 21 thereto. The opposite terminals of the conductors are engaged about the front terminals of a series of bolts or 105 screws 22 which are extended through the body plate 5 and are arranged along a line extending longitudinally thereof, one of the screws 22 being located directly beneath each of the several lamp sockets 6 and 14. The 110

headed terminals of the screws 22 are countersunk in the rear surface of the body plate 5 and nuts 23 are threaded upon the front terminals of the screws and secure the 5 terminals of the conductors 21 thereto.

The portion of the marginal flange 8 opposite the conductor 16 is provided with an aperture receiving a socket member 24 having a threaded axial bore 25 in one terminal 10 and a transverse aperture 26 in the opposite terminal, the latter receiving a screw 27 whereby the socket member is secured in position upon the body plate. A conductor 28 is secured by the securing member 27 and 15 is electrically connected at its opposite terminal with the conductor 16 whereby an electrical connection between the socket member 24 and the several contact strips 12 is established.

20 For convenience in establishing an electrical connection between the socket member 24 and the pole of the battery opposite that engaged by one of the screws 22, a flexible conductor 29 is provided and carries, at one 25 terminal, a threaded stem 30 engageable in the threaded terminal of the socket member 24 whereby the terminal of the flexible conductor is detachably secured thereto. The opposite terminal of the flexible conductor is 30 provided with a contact pin 31 for engagement with the pole of the battery.

The several screws 22 are extended forwardly through the cover plate 7, as suggested in Fig. 3, for convenience in engaging 35 the pole of a battery therewith and these projecting terminals of the screws constitute electrodes or contact points.

Another advantage of the utilization in 40 the expansible lamp socket 14 resides in the convenience afforded in testing electric lamps having the reflectors 32 attached directly thereto as in numerous conventional types of flash lights. Owing to the expansibility of the socket, the latter readily ex-

pands to such extent as to accommodate the 45 lamp base and reflector.

The several lamps 10 are designed for operation by electrical currents of varying voltages and by engaging the contact pin 31 at one terminal of the flexible conductor 29 50 with one pole of the battery and engaging the opposite pole of the battery successively with the several screws 22, the strength of the battery may be readily determined by the brilliancy of the filaments of the lamps. 55 If preferred, a suitable type of reflector 32 may be attached to one of the lamps 10, preferably the one engaged in the split expansible socket 14.

What I claim is:

1. A battery tester including a body plate, a plurality of incandescent lamps supported therein, a contact point arranged opposite each incandescent lamp and electrically connected therewith, said contact points being 60 engageable with one pole of an electric battery, a socket member electrically connected with the several incandescent lamps, and a flexible contact element detachably engaged with the socket member engageable with the 65 opposite pole of the battery.

2. A battery tester including a body plate, a series of incandescent lamps arranged thereon, a contact point arranged opposite each lamp and being electrically connected 70 therewith, said contact point being engageable with one pole of an electric battery, a socket member secured to the body plate having electric connection with the several lamps, a flexible conductor, a terminal carried by the conductor engageable with the 75 socket member, and a contact pin at the opposite terminal of the flexible conductor engageable with the opposite pole of the electric battery.

85 In testimony whereof I affix my signature hereto.

LEWIS LINCOLN LASKA.
